DESIGN FOR A CHECK WRITER

John P. Hunter, East Orange, N. J., assignor to Safeguard, Inc., New York, N. Y., a corporation of Delaware

Application February 23, 1935, Serial No. 55,587

Term of patent 14 years

To all whom it may concern:

Be it known that I, John P. Hunter, a citizen of the United States, residing in East Orange, New Jersey, have invented a new, original, and ornamental Design for a Check Writer, of which the following is a specification, reference being had to the accompanying drawing, forming part thereof, in which:

Figure 1 is a perspective view, and
Fig. 2 is a plan view of the check writer.

I claim:
The ornamental design for a check writer, substantially as shown.

JOHN P. HUNTER.
